UNITED STATES PATENT OFFICE.

GEORGE J. KUHN, OF ADAMS, ILLINOIS.

SCREW-DRIVER-GRIPPING DEVICE.

Application filed November 28, 1923. Serial No. 677,395.

The object of my invention is to provide a screw driver having a gripping means for engaging the screw for starting it, the parts being simple, durable and comparatively inexpensive.

More particularly, my invention comprises a screw driver having two screw engaging blades, one of which is used when the screw is first started and the other one is used after the screw has partially entered into the material for completing the operation of screwing the screw into the wood or other material.

Still a further object is to provide a fixed jaw on the screw driver and a movable jaw member for engaging the screw head when the screw is first engaged, and to provide a trip finger for moving the movable jaw member to position where the screw may be disengaged from the screw driver.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a perspective view of my improved screw driver and gripping means.

Figure 2 is a side elevation of the same.

Figure 3 is a detail, sectional view taken on line 3—3 of Figure 2.

Figure 4 is a sectional view taken on line 4—4 of Figure 3, showing the two screw driver blades arranged at right angles to each other; and

Figure 5 is a front view of one end of the screw driver and gripping means.

In the accompanying drawings, I have used the reference numeral 10 to indicate generally a screw driver handle, in which is mounted the shank 11 of the screw driver.

The shank 11 is provided with an enlarged portion 12, the purpose of which will be hereinafter more fully set forth.

The enlarged portion 12 is arranged between the ends of the shank 11.

On the free end of the shank 11 is formed a jaw member 13 having an opening 14 therein of substantially the same size and shape of one half of an ordinary screw head.

The screw driver blade 15 is formed near the jaw 13 on the shank 11 and projects into the opening 14 just mentioned.

Secured to the shank 11 is a resilient arm

16 held in position by the screws 17, which extend therethrough and project into the enlarged portion 12. The enlarged portion 12 is provided for accommodating the screws 17 whereby the arm 16 is fixed.

The arm 16 rests substantially against one edge of the shank 11 and has its forward end provided with a jaw member 18 which has an opening 19 therein. The opening 19 is substantially the same size as the opening 14 so that the openings 14 and 19, when placed side by side form a complete opening for receiving the head of an ordinary screw.

The jaw member 18, together with the arm 16 is capable of movement so that the jaw member 18 may properly be termed a movable jaw member.

The screw driver blade 15 is practically concealed and received within the openings 14 and 19.

Pivotedly mounted on the screw 20 is an actuating finger 21 having the finger engaging piece 22 thereon. The actuating finger 21 is arranged substantially at right angles to the arm 16. The arm 16 projects out beyond the side of the shank 11 so that when the finger 21 is swung on its pivot, the forward edge thereof will engage the arm 16, spacing the jaw member 18 from the jaw member 13 to permit a screw head to be received between the jaws and to be engaged by the screw driver blade 15.

The position that the arm 16 and the jaw member 18 will assume when the finger 21 is moved, is shown in Figure 1 of the drawings in dotted lines.

The actuating finger 21 is provided with a pair of bowed or curved parts 23 which permit the finger 21 to clear the enlarged portion 12 of the shank 11.

The jaw member 13 is formed with a screw driver blade 24 which is used like an ordinary screw driver and which cooperates with the jaws 13 and 18 in starting small screws, which do not fit snugly in the gripping device.

In the practical operation of my invention, the screw head is received within the openings 14 and 19 in the jaws 13 and 18 and the screw driver blade 15 extends into the notch formed in the screw head.

The jaw members 13 and 18 will retain the screw in position and the screw driver blade 15, when rotated will cause the screw to be "started" and enter the material desired.

After the screw has been started some-

what, then it is necessary to move the actuating finger 21 to the dotted line position in Figure 1, at which time the screw head may be disengaged from the jaw members 13 5 and 18 and then the operation completed by using the screw driver blade 24 in the ordinary manner.

The arm 16 is of resilient material and will normally remain in the position shown 10 in solid lines in Figure 1 of the drawings.

After the screw has been engaged then the screw driver blade 24 is used.

It will be seen that I have provided a 15 positive screw engaging means which may function properly for commencing the screw and thereafter by an independent screw driver blade, the placing of the screw may be completed.

It will be seen that I have provided on 20 the shank 11 two independent screw driving blades for first starting the screw and then completing the positioning of the same.

Some changes may be made in the construction and arrangement of the various 25 parts of my invention, without departing from the real spirit and purpose of my in-

vention and it is my intention to cover by my claim, any modified forms of structure or use of mechanical equivalents which may be reasonably included within their scope. 30

I claim as my invention:

A screw driver having means thereon for gripping the head of a screw, said means comprising a jaw on the shank of said screw driver near the screw slot engaging end 35 thereof, a depression in said jaw for receiving substantially one half a screw head, a blade in said depression for engaging the slot of the screw, said blade having substantially one half thereof extending into 40 said depression, a second jaw yieldingly supported on said shank having a depression therein for receiving the other half of the screw head and so arranged as to yieldingly hold the same, the other half of said blade 45 extending into the depression in said second jaw, and a lever mounted on said shank for disengaging said yielding jaw from said screw head.

Des Moines, Iowa, November 13, 1923.

GEORGE J. KUHN.
